UNITED STATES PATENT OFFICE.

FREDERICK BEIERMEISTER, JR., OF TROY, NEW YORK.

DESIGN FOR AN APPAREL-COLLAR.

SPECIFICATION forming part of Design No. 19,314, dated September 17, 1889.

Application filed July 17, 1889. Serial No. 317,810. Term of patent 14 years.

To all whom it may concern:

Be it known that I, FREDERICK BEIERMEISTER, Jr., residing in the city of Troy, county of Rensselaer, and State of New York, have 5 invented and produced a new and original Design for Apparel-Collars, of which the following is a specification, reference being had to the accompanying drawings, forming part thereof.

10 Figure 1 of the drawings is a view in perspective of my newly-designed collar ready and in form for use. Fig. 2 is a view in plan of the same collar laid out flat.

The leading feature of my design consists 15 of a collar provided with the ordinary button-holed bottom part or band and a turn-down or top part having a novel outline formed by its outer and inner edges. The outline formed by the outer edge from a point near 20 one end to a similar point near the other end is parallel with the dividing-line which separates the parts. From such points at the ends of such parallel part the outline diverges and extends for a short distance on straight lines, 25 forming with the parallel part similar obtuse angles. Thence it diverges on straight lines, forming acute angles with the last-mentioned diverging lines, and extends to the dividing-

line which separates the two parts. The outline formed by the inner edge is that of a 30 slightly and uniformly curved line.

A is the bottom or band part, having the button-holes A'.

B is the top or turn-down part, separated from the bottom part by the dividing-line B', 35 which forms the outline of the inner edge of the top part.

C is that part of the outline formed by the outer edge of the top part, which is parallel to the dividing-line B'. 40

C' are the straight diverging lines which form the obtuse angles D with the parallel part, and C² the straight diverging lines which form with the straight lines C' the acute angles D' and extend to the dividing 45 line B'.

What I claim is—

The design for an apparel-collar herein shown and described.

In testimony whereof I have hereunto set 50 my hand this 15th day of July, 1889.

FREDERICK BEIERMEISTER, JR.
